UNITED STATES PATENT OFFICE.

EDWARD CHISMON GOLDING, OF LONDON, CHARLES PERKS, OF BARNES, AND ALFRED JOSEPH PEMBERTON, OF SOUTHBEND-ON-SEA, ENGLAND.

SUNBLIND AND THE LIKE.

Application filed August 29, 1923. Serial No. 659,976.

To all whom it may concern:

Be it known that EDWARD CHISMON GOLDING, British subject, of 28, Gumleigh Road, Ealing, London, CHARLES PERKS, of 21, 5 Cleveland Road, Barnes, British subject, and ALFRED JOSEPH PEMBERTON, of 6, Elizabeth Road, Southend-on-Sea, British subject, have invented certain new and useful Improvements in Sunblinds and the like, 10 of which the following is a specification.

This invention relates to sunblinds and the like and its object is to provide improved mechanical means adapted for actuation by power or by hand for the purpose 15 of projecting the blind for use and withdrawing it when not required for use.

According to this invention the movable rail forming the free edge of the blind is protected from or drawn towards the spring 20 influenced roller on which the blind is wound by the action of two rods pivotally connected to the rail and to two travellers mounted to move upon guides parallel with the rail and roller and moved simultaneously in opposite directions by hand or power 25 operated mechanism which may consist of an endless chain or band to opposite runs of which the travellers are attached or other traversing means. When the blind is wound 30 up and out of use, the rail is in proximity to the horizontal guides, and the rods connecting the travellers with the rail lie almost in line with these guides, but upon operating the driving chain to move the 35 travellers along the guides a thrust will be imparted to the rail through the medium of the rods and the rail will in consequence be moved towards the projected position, the rods moving angularly with regard to 40 the rail as well as longitudinally in relation to the guides.

In one way of carrying the invention into practical effect a guide rail composed of some suitable material such as profile iron 45 is mounted in a horizontal position adjacent the usual spring influenced blind roller, and wheels or sprockets mounted at opposite ends of this rail carry an endless chain or band whose upper and lower runs are located above and below the guide rail. The lateral edges of the guide rail form runways or tracks along which two travellers connected with the upper and lower runs of the endless band are caused to move in op-

posite directions when the endless band is 55 operated by the wheels or sprockets.

A rail to which the free edge of the blind fabric is attached is supported by two arms, each of which is pivotally attached at one end to a traveller and at the other end to 60 the movable blind rail. When the blind is retracted, these arms are disposed at a slight angle to the movable blind rail and to the horizontal guide so that upon motion being imparted to the endless driving band 65 in the appropriate direction the thrusts imposed upon the arms by the travellers cause the blind rail to move away from the horizontal guide rail to an extended position. By reversing the motion imparted to the 70 endless band the blind may be withdrawn to the retracted position again.

The endless band may be driven by power or manually operated mechanism located adjacent or at a distance from the blind operating means. Where it is desired that the blind when fully projected shall assume a sloping position, the pivotal axes about which the arms turn with respect to the travellers 75 are inclined from the vertical. 80

The invention is hereinafter more fully described with reference to the accompanying drawings in which:—

Figs. 1 and 2 are front elevation showing diagrammatically one practical form of blind 85 operating mechanism in retracted and extended positions respectively.

Fig. 3 is a side elevation of the same showing the blind extended.

Fig. 4 is a fragmentary side elevation 90 showing a modified form of construction and,

Fig. 5 is a front elevation of a further modified form wherein the blind is shown in a partly extended position. 95

Referring to Figs. 1 to 3 it will be seen that the blind *a* composed of canvas or other suitable fabric is wound upon a spring influenced roller *b* and attached at its free edge to a movable rail *c* in the usual manner. The mechanism for actuating and supporting the blind in its various positions is mounted adjacent the roller *b* and comprises a length of profile iron *d* set horizontally with its flanges forming parallel 100 tracks or guide rails along which two travellers *e* and *f* fitted with rollers are arranged to move. 105

These travellers *e* and *f* are connected to the upper and lower runs of an endless band composed partly of chain *g* and partly of rope *h*. The chain *g* engages a sprocket 5 wheel *i* at one end of the guide rail and the rope *h* passes around a pulley *j* at the other end of the rail *d*, thus upon rotary motion being imparted to the sprocket wheel the travellers *e* and *f* will move in opposite directions along the guide rail *d*.

The movable rail *c* at the free edge of the blind is connected to the travellers by arms *k* pivoted to the travellers in such manner as to turn about axes inclined away from the 15 front of the building protected by the blind in order that said arms may move from a substantially horizontal position adjacent the guide rail when the blind is retracted to a downwardly sloping position when the 20 blind is projected.

By connecting these arms *k* to the ends of the rail *c* through the medium of short cranks *l* as shown, a small amount of lost motion between the parts is provided for the 25 purpose of facilitating the initial movement of the parts either when projecting or withdrawing the blind. Without this lost motion, it would be difficult to start the operation of the device from either of its extreme 30 positions, owing to the angularity which the arms *a* have to the rails in either of these positions.

In order that the weight of the blind *a*, rail *c* and arms *k* may be adequately supported in all positions, auxiliary arms *m* pivoted to turn about sloping axes in fixed brackets *m'* are pivotally connected to the arms *k* at about their centres of length. In the construction shown, the mechanism is 40 driven by an electric motor *n* geared direct by worm gearing *n'* to the sprocket wheel *i*.

The modified construction illustrated in Fig. 4 differs from that just described only in so far that the auxiliary arms *m''* are arranged above instead of below the main arms *k*, and in the manner of pivotally mounting the arms *k'* upon the travellers and the arms *m''* upon the fixed brackets *m*.

In the arrangement illustrated in Fig. 5 in 50 order to enable a larger degree of projection to be had relative to the width of the blind, both travellers are arranged to move the full length of the guide instead of only half the length as in the construction first described. 55 That is to say the travellers *e* and *f* are arranged upon superposed guide rails *d'* in such manner that they can pass one another and longer arms *k''* capable of projecting

the blind rail to a greater extent are employed.

The arms cross one another when the blind is being withdrawn to the retracted position.

By providing an electric motor or other suitable power unit to drive the endless 65 chain the operation of the blind may be conveniently controlled from a distant point. If preferred however, the blind may be manually operated through the medium of suitable transmission mechanism connected with 70 the blind projecting mechanism above described.

We claim:

1. A device of the class described comprising a flexible blind, a spring roller upon 75 which said blind is wound, a stiff rail secured along the outer edge of said blind, guiding means extending parallel to said roller, rods for projecting and retracting said blind, having their inner ends slidably 80 engaged with said guiding means, means for sliding the inner ends of said rods along said guiding means to project and retract said blind, and short crank arms connecting the outer ends of said rods to said rail, 85 whereby to permit a small amount of lost motion between the parts for the purpose set forth.

2. A device of the class described comprising a flexible blind, a spring roller upon 90 which said blind is wound, a stiff rail secured along the outer edge of said blind, a pair of guide-rails arranged in superposed relation extending parallel to said roller, a pair of rods for projecting and retracting 95 said blind having their outer ends connected to said stiff rail, the inner end of one rod being slidably engaged with one of said guide-rails and the inner end of the other rod being slidably engaged with the lower 100 edge of said guide-rail, the inner end of each rod traversing the full length of the guide rail with which it is engaged, an endless band mounted for movement with its upper and lower stretches disposed adjacent the 105 upper and lower guide-rails respectively, means for operating said band, means connecting the inner end of one of said rods to the upper stretch of said band, and means connecting the inner end of the other rod to 110 the lower stretch of said band.

In testimony whereof we affix our signatures.

EDWARD CHISMON GOLDRING.
CHARLES PERKS.

ALFRED JOSEPH PEMBERTON.
